(57) **CLAIM**

The ornamental design for a multispectral camera as shown and described.

DESCRIPTION

FIG. 1 is a top, front, and left side perspective view of a multispectral camera, showing my new design;

FIG. 2 is a top, front, and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

1 Claim, 4 Drawing Sheets
